L. PENGILLY

IGNITION HEAD FOR CIGAR AND CIGARETTE LIGHTERS

Filed March 4, 1924

INVENTOR.
Lewis Pennington
BY *Henry J. Webster*
ATTORNEY

UNITED STATES PATENT OFFICE.

LEWIS PENGILLY, OF STOCKTON, CALIFORNIA.

IGNITION HEAD FOR CIGAR AND CIGARETTE LIGHTERS.

Application filed March 4, 1924. Serial No. 696,767.

To all whom it may concern:

Be it known that I, LEWIS PENGILLY, a citizen of the United States, residing at Stockton, county of San Joaquin, State of California, have invented certain new and useful Improvements in Ignition Heads for Cigar and Cigarette Lighters; and I do declare the following to be a full, clear, and exact description of the same, reference being had to the accompanying drawings, and to the characters of reference marked thereon, which form a part of this application.

This invention relates to electrical ignition heads for cigar and cigarette lighters, and particularly to a head to be used in connection with that form of lighter which includes a current-carrying cord wound on a spring reel, mounted on the dashboard of an automobile, such as is shown in my co-pending application, Serial No. 685,882, filed January 12th, 1924.

The principal object of this invention is to construct the head in such a manner that it may be very easily separated into its various parts, so that the heating elements, or any other part apt to break or wear out, may be readily replaced.

Devices of this character are provided with switch means automatically closed when the head is pulled out of its socket adjacent the reel, and another object of my invention is to provide means for enabling the head to be withdrawn without said switch becoming closed. This enables the head to be worked on without danger of any short circuits being made, and without having to disconnect any of the wiring at the reel or beyond the same.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side outline of a combined cigar and cigarette lighting structure, showing my improved ignition head and switch means.

Fig. 2 is a longitudinal section of the ignition head and switch.

Fig. 3 is a section on line 3—3 of Fig. 2.

Fig. 4 is a section on line 4—4 of Fig. 2.

Fig. 5 is a longitudinal section of the removable connection-stem of the head.

Referring now more particularly to the characters of reference on the drawings, the numeral 1 denotes the casing of a spring-reel structure of common form, which of itself forms no part of my invention.

From this casing a rigid tube 2 extends tangentially, being adapted to be secured to and project through a dashboard 3 or the like.

The ignition head comprises in general a head portion proper, and a stem portion extending at right angles to the axial plane of the head and adapted to fit in the tube 2.

The head comprises a hollow circular member 4 with a portion 5 concentric therewith but of reduced diameter, the latter portion having a short hollow stem 6 projecting at right angles to the axial plane thereof. The opposite ends of members 4 and 5 are open and closed respectively, the rim of the former serving as a seat for an insulation disc 7 of mica or the like, removably held in place by means of a flanged ring or cap 8 having a snug fit on the member 4.

On the outer face of the disc 7 is a heating element 9, secured thereon by screws 10, which project through the disc and are adapted to engage and press against opposed spring members 11 formed as part of strips 12 mounted in spaced relation in an insulation core 13 removably seated in the portion 5.

Adapted to removably fit in the stem 6 is an insulation core 14, having embedded therein for a portion of its length spaced pins 15, projecting beyond the inner end of said core and adapted to removably engage the strips 12 and seat in the core 13 by reason of circular sockets 16 formed in said strips 12 and core 13, as shown in Fig. 4.

The core 14 is longitudinally split beyond the inner ends of the pins 15, one half 17 of the split portion being removable but normally secured thereto as by means of a split-band 18.

The flexible leads or cables 19 from the reel project into the core 14 along the split line, and are secured to the adjacent ends of the pins 15 by soldering or otherwise. In this manner the necessary connections between said pins and cables may be easily

made and inspected when desired without the use of screws or the like, and without having to bind the same with tape, and yet such connections are normally concealed and protected.

A metal sleeve 20 envelops the core 14, and is removably mounted on the stem 6 with a snug frictional fit.

This sleeve has a running fit in the tube 2, and is adapted to be inserted therein and withdrawn therefrom at will.

Mounted on the tube 2 adjacent the plane of the inner end of the sleeve 20 when the latter is fully telescoped in said tube is an insulation ring 21, having a spring band 22 extending for a certain distance about the periphery of the ring. One end of this band is secured to the ring and to a lead 23 of the wiring of the reel.

20 A pin 24, preferably in the form of a set screw, is located in the ring 21 under the free end of the band 22, and engages the tube 2. This member 24 not only serves as a means to secure the ring 21 to the tube 2, but when engaged by the band 22, closes a circuit from lead 23 to ground through the metal tube 2, which causes the circuit to be closed through leads 19 and element 9.

Slidably and radially mounted in the ring 30 21 and projecting through the tube 2 is a pin 25 having an insulated head adapted to bear against the band 22 intermediate the ends of the latter. This pin, when the spring band is engaged with the contact pin 24, projects 35 beyond the inner periphery of the tube 2, and is adapted to be engaged and moved outwardly by the rounded or tapered end 26 of the sleeve 20 when the latter is fully inserted in the tube 2. This movement of 40 the pin 25 raises the spring band 22 from contact pin 24, breaking the circuit.

In operation then it will be seen that as the head as a unit is drawn away from the tube 2, the switch to the element 9 will automatically be closed.

Should it be desired however to hold the switch open while still holding the head away from the tube 2, it is only necessary to unseat the sleeve 20 from the stem 6, slide 50 it over the core 14 and along the extended cords 19, and press it into a fully telescoped position in the tube 2. This, as previously explained will break the circuit. The head may therefore be worked on in a convenient 55 position without fear of causing any short circuit, and the heating element may be instantly replaced, or the entire structure taken apart for inspection or any necessary adjustments or repairs.

60 My device however has still another valuable feature. The element takes an appreciable time to heat to the necessary degree, and heretofore it has been necessary to definitely hold the head away from the reel 65 while the element is heating up.

In my improved structure, however, the spring switch-band 22 presses the pin 25 inwardly of the tube with a strength greater than that of the spring of the reel tending to draw the sleeve 20 in and thus raise the 70 pin and break the circuit.

Therefore by drawing the sleeve out of the tube just a sufficient distance to cause the switch to be closed and the pin to project into the tube beyond said sleeve, the 75 latter (to which the ignition head is attached) may be left in and supported by the tube while the element is heating. Then the element is ready for instant use the moment the head is drawn clear of the tube. 80

At the same time, should the operator decide not to use the head after the element has thus been heated, all he has to do is give a slight inward push on the head, which of course will instantly open the 85 switch.

From the foregoing description it will be readily seen that I have produced such a device as substantially fulfills the objects 90 of the invention as set forth herein.

While this specification sets forth in detail the present and preferred construction of the device, still in practice such deviations from such detail may be resorted to as do not form a departure from the spirit 95 of the invention, as defined by the appended claims.

Having thus described my invention what I claim as new and useful and desire to secure by Letters Patent is:

1. An ignition head for cigar and cigarette lighters comprising an open-topped body member, a disc adapted to rest on the rim of the body, a heating element carried by the disc, means independent of the disc 105 for removably holding said disc in place, and contact means in the body with which the heating element is then automatically engaged.

2. An ignition head for cigar and cigarette lighters comprising an open-topped body member, a disc adapted to rest on the rim of the body, a heating element carried by the disc, a flanged ring independent of the disk adapted to removably fit onto the body and then engaging and holding the disc seated, and contact means in the body with which the heating element is then automatically and removably engaged.

3. An ignition head for cigar and cigarette lighters comprising an open-topped body member, a disc adapted to rest on the rim of the body, a heating element carried by the disc, means for removably holding said disc in place, screws securing the element on the disc and projecting through the latter, and spaced spring contact strips mounted in the body under the disc and with which the screws are adapted to engage when the disc is seated on the rim.

4. An ignition head for cigar and cigarette lighters comprising an open-topped body member having adjacent its opposite end a hollow stem portion, a heating element mounted on the body at its open end, contact means engaging said element mounted in the body, an insulation core removably mounted in the stem, and contacts mounted in and projecting beyond said core and detachably engaged with the body contact means. 50
5. A structure as in claim 4, in which a sleeve covers said core and is removably mounted onto the stem. 60
- 15 6. An ignition head for cigar and cigarette lighters comprising a heating element, leads extending therefrom, a tubular sleeve provided with said element, a tube into which said sleeve fits, a switch arranged in connection with the tube adjacent the inner end thereof and interposed in the leads, said switch including an insulation ring fixed on the tube a spring band on the ring and a movable pin engaged thereby and projecting radially through the tube in the path of movement of the inner end of the sleeve, said pin being normally forced inwardly of the tube by said band and the latter offering resistance to outward movement of the pin, and means whereby the switch will be closed only when said pin is in its innermost position. 65
- 20 7. An ignition head for cigar and cigarette lighters including with a fixed tube, a sleeve removably telescoped in the tube, a heating element normally supported by the sleeve at the outer end thereof, but removable therefrom at will, and extensible leads connected to the element and passing through the sleeve but not attached thereto, whereby said element and leads can be withdrawn from the sleeve without disturbing the latter and without disconnecting the element and leads from each other. 70
- 25 8. An ignition head for cigar and cigarette lighters including with a fixed tube, a sleeve removably telescoped in the tube, a heating element normally supported by the sleeve at the outer end thereof, but removable therefrom at will, extensible leads projecting into the inner end of the sleeve, disconnectible connections between the element and said leads, and means whereby said connections can only be disconnected from each other when the element is withdrawn from the sleeve. 75
9. An ignition head for cigar and cigarette lighters including with a fixed tube, and switch means mounted in connection therewith, a heating element normally positioned adjacent the outer end of the tube, extensible leads connected to the element and passing through the tube, said leads being interposed in the switch-circuit, means whereby the switch will normally be automatically closed when the element is moved away from the tube, and means whereby the switch may be held open even when the element and the leads connected thereto are moved away from the tube. 80
10. An ignition head for cigar and cigarette lighters including with a fixed tube, and switch means mounted in connection therewith, a heating element normally positioned adjacent the outer end of the tube, extensible leads connected to the element and passing through the tube, said leads being interposed in the switch-circuit, and a member controlling the opening and closing of the switch normally mounted in connection with but independent of the element and of the leads. 85
11. An ignition head for cigar and cigarette lighters including a fixed tube, a stem removably mounted therein, extensible leads connected to the stem, and a heating element at the outer end of the stem, said element facing at right angles to the stem, whereby the element may be positioned in either a horizontal or a vertical plane when the stem is inserted into the tube. 90

In testimony whereof I affix my signature.

LEWIS PENGILLY.
